UNITED STATES PATENT OFFICE.

OTTO A. LEHMAN, OF HOBOKEN, NEW JERSEY.

DESIGN FOR A SHOPPING-BAG.

SPECIFICATION forming part of Design No. 31,053, dated June 20, 1899.

Application filed May 23, 1899. Serial No. 717,960. Term of patent 7 years.

To all whom it may concern:

Be it known that I, OTTO A. LEHMAN, a citizen of the United States, and a resident of Hoboken, in the county of Hudson and State of New Jersey, have invented and produced a new and original Design for Shopping-Bags, of which the following is a specification.

The leading feature of my design consists in a shopping-bag presenting when viewed from its opposite sides a body portion tapering outwardly as it extends upwardly from the bottom and then inwardly toward the top; a band portion extending along the upper edge, surmounted by a pair of uprising projections connected at their tops by a bar and separated below the bar by a band which when viewed from one side extends along down the side of the bag and when viewed from the opposite side extends down to the lower edge of the band at the upper edge of the body of the bag, the said body portion being further provided with curved handles uprising from each of its two sides.

In the accompanying drawings, Figure 1 is a view of the bag from one side. Fig. 2 is a

view of the bag from the opposite side, and Fig. 3 is an end view.

A represents the body of the bag; B, the band across its upper edge; C C', the projections uprising from said edge band; D, the bar connecting the tops of the said projections; E, the band which separates the said projections below the bar D when viewed from one side, and E' the band which separates the said projections when viewed from the opposite side. The curved handles uprising from each of the two opposite sides of the bag are denoted by F F'.

What I claim is—

The design for a shopping-bag, substantially as herein shown and described.

In testimony that I claim the foregoing as my invention I have signed my name, in presence of two witnesses, this 16th day of May, 1899.

OTTO A. LEHMAN.
